TOOL MOUNTING

Thomas E. Brooks, Clarinda, Iowa, assignor to Lisle Corporation, Clarinda, Iowa, a corporation of Iowa

Application October 27, 1953, Serial No. 388,653

5 Claims. (Cl. 77—2)

This invention relates to a tool mounting for a work contacting tool carrier such as shown in my co-pending application, Serial No. 310,680, filed September 20, 1952, which has issued as Patent No. 2,780,115, dated February 5, 1957, the present tool mounting being adapted for such tools as cylinder ridge reamers of the type shown in Olson Patent No. 1,927,594.

One object of the present invention is to provide a tool mounting for a tool carrier wherein the tool is a combined cutting and guide blade and the carrier has a socket to receive it, the socket being enlarged at two points for the reception of a spring at each point, which springs form the sole backing support for the tool.

Another object is to provide one of the springs located behind the cutting edge of the tool and the other behind the guide edge thereof for efficient cutting action of the tool in relation to the work.

Still another object is to provide a simple means for holding the springs in their enlargements when the tool is removed from the tool carrier, this means consisting of projections past which the springs can be threaded to enter them into their sockets.

Still a further object is to provide a stabilizer blade connected with the tool carrier and cooperating with the tool in its tool mounting to minimize vibrations in the operation thereof during the reaming of the cylinder, the stabilized blade being in the form of a resilient sheet metal blade attached to the tool carrier and having a part inclined relative to the adjacent cylinder wall, this part terminating just ahead of the cutting portion of the tool blade.

More particularly, the stabilizer is formed of flat spring steel and its function is to contact the wall of the cylinder bore before the cutter makes contact and thus serves to stabilize the reamer in the bore so that if desired a light scraping cut can be made with the cutter or by heavier pressure on the cutter, by means of the reamer expansion screw, the resilient stabilizer will give way and permit a heavy cut to be made.

With these and other objects in view, my invention consists in the construction, arrangement and combination of the various parts of my tool mounting whereby the objects contemplated are attained as hereinafter more fully set forth, pointed out in my claims and illustrated in the accompanying drawing wherein;

Figure 1 is a plan view with parts broken away showing a ridge reamer in which my tool mounting is used, the tool being adjusted for minimum operating size or diameter.

Figure 2 is a similar view showing the tool adjusted for maximum possible diameter and showing one of the two carriers in section with my tool mounting illustrated in section.

Figure 3 is a side elevation of Figure 2 with a portion thereof in section on the indicated line 3—3 of Figure 2.

Figure 4 is a three-quarter view of a tool carrier with my tool mounting and stabilizer blade applied thereto

2

looking in the direction of the arrow 4 on Figure 2; and

Figures 5 and 6 are detail horizontal sectional views on the lines 5—5 and 6—6 respectively of Figure 3.

5 On the accompanying drawing I have used the reference numeral 10 to indicate in general an upper body member and 12 a lower body member. The upper body member as shown in Figure 2 is in the shape of a 3-arm spider having an upstanding boss 22 at its center; whereas the outline of the lower member 12 is circular. The body member 10 has a bore 14 therein and the body member 12 is provided with a corresponding bore threaded as indicated at 16. An adjusting screw having a shank 18 and threads 20 passes through the boss 22 and the bore 14, and is threaded into the bore 16.

A head 24 on the adjusting screw 18—20 may be engaged by a wrench for rotating the adjusting screw as from the position in Figure 3 to one wherein the lower end of the threaded portion 20 is about even with the bottom of the member 12 whereupon the tool is adjusted for minimum size as in Figure 1 as distinguished from maximum size as in Figure 3.

The upper body member 10 is provided with three guide grooves 26 and the lower body member 12 is provided with three companion guide grooves 28 which are channel shaped. They are also inclined as evident from an inspection of Figure 3. A carrier member 30 is provided for each set of grooves 26 and 28 and has upper and lower edges slidable in the respective grooves.

30 Two of the members 30 carry work contacting ribs 36 to engage the internal surface of a cylinder or the like and the third member 30 is provided with a vertical slot 39 in which is received a tool 38. Also, each of the carrier members 30 is provided with a spring receiving notch 42 which receives a coil spring 46 that surrounds the tool and is also received in a notch 44 of the tool blade 38.

The tool blade 38 has a cutting portion 40 and a work contacting portion 41. The cutting blade portion 40 may be an insert of tungsten carbide to resist wear of the cutting tool. The spring 46 tends to keep the carrier members 30 biased toward the center of the tool and to retain them in the guide slots or grooves 26 and 28 of the body members 12 and 10. It also moves the carrier members 30 inwardly when the adjusting screw 18—20 is rotated counterclockwise in order to permit adjustment to a smaller diameter of cylinder by permitting the body member 12 to recede from the body member 10.

Each of the carrier members 30 is provided with a supporting lug 48 adapted to contact the upper surface of an engine cylinder block 50 as shown in Figure 3 when the tool is used as a ridge reamer for removing a ridge 52 from the inner surface of the cylinder. When used in this manner suitable power means or a wrench is applied to the hub 22 for rotating the reamer clockwise in Figure 2 so that the cutting blade 40 may cut off the ridge 52 of the cylinder wall until this portion of the cylinder is coincident with the rest of the cylinder wall against which the tool 38 is held by a pair of springs 54. These springs also permit the tool to follow an out-of-round cylinder.

With further reference to the springs 54, they are mounted in enlarged sockets 56 of the slot 39, one of them being located approximately centrally behind the cutter blade 40 and the other approximately in alignment with the work contacting portion 41 of the blade 38. The two springs 54 constitute the sole backing means for the cutter blade and are relatively stiff so as to exert considerable cutting pressure of the blade against the ridge 52 when desired, the tension of the springs of course being adjusted by the screw 18—20 which sets the position of

the carrier members 30 or causes them to positively assume a predetermined cylinder size. The resiliency of the springs 54 permits the blade 38 to move back in the slot 39 and feed the cutting edge 40 against the ridge 52 with just the desired pressure depending on the setting of the screw 18-20.

The preferable adjustment for this screw is one in which the tool is expanded with the work contacting ridges 36 of two of the carriers 30 in contact with the cylinder wall 50 (indicated by dashed lines in Figure 2) and the corresponding face of the tool carrying member 30 slightly spaced from the cylinder wall. The two members 30 having the ribs 36 are undercut at 37 to clear the cylinder ridge 52. The initial position of the blade or tool 38 is as shown by dotted lines in Figure 2 and therefore in the solid line position shown, the springs 54 are compressed to cause the cutter 40 to work its way through the ridge 52 and stop cutting when the ridge has been trimmed off level with the wall of the cylinder 50 below the ridge due to a portion 38a of the tool 38, which projects radially slightly beyond the cutting edge at the inner end of the cutter 40, at that time contacting the wall with a pivoting action about the work contacting portion 41. To aid in this respect, the blade 38 has a countersunk clearance portion 40a between the outer end portions of 40 and 41.

To retain the springs 54 in their sockets 55 when the blade 38 is removed, one side of the socket is peened to form a projection 62 after the springs are inserted. A broken spring can be removed for replacement however by "threading" the spring past the projection.

During the reaming operation the tool is stabilized by a blade 56-58 secured to the tool carrier blade 30 by a pair of screws 60. This stabilizer blade is formed of flat spring steel bent to shape with two flanges 56 and 58, 56 being an anchoring flange and 58 a cylinder contacting flange initially in the position shown by solid lines in Figure 2, but bent back to the position shown by dotted lines during operation. The function of the stabilizer blade 56-58 is to contact the wall of the cylinder bore 50 before the cutter 40 makes contact therewith and thus serve to stabilize the reamer in the bore so that if desired a light scraping cut can be made without chattering action of the cutter 40. At the same time, if heavier pressure for a heavier cut is desired, the reamer can be so adjusted and the flange 58 will "give" and permit such heavy cut without interfering with the action of the cutting blade 40. The stabilizer blade makes possible the operation of the reamer for light cuts with one hand or with long extension wrenches in close quarters which is often found quite desirable.

Some changes may be made in the construction and arrangement of the parts of my tool mounting without departing from the real spirit and purpose of my invention, and it is my intention to cover by my claims any modified forms of structure or use of mechanical improvements which may be reasonably included within their scope.

I claim as my invention:

1. Tool mounting means for a carrier member comprising a slot in the carrier member, an elongated blade loosely received in said slot and having a cutting edge adjacent one end thereof and a work contacting portion adjacent the other end thereof, said ends being independently slidable into and out of said slot, a pair of enlarged spring sockets in said slot, a spring in each socket back of said blade and constituting the sole supporting means therefor in opposition to the work, one of said springs being located back of said cutting edge and the other back of said work contacting portion of said blade with said springs exerting substantially equal pressures on said cutting edge and said work contacting portion of said blade, and means projecting into said spring sockets

at the outer ends thereof past which the springs may be threaded and thereafter retained entirely within said sockets by said projecting means.

2. A tool mounting comprising a tool carrier and an elongated blade having a cutting edge portion and a work contacting portion longitudinally spaced from each other and adjacent opposite ends of said blade, said tool carrier having a slot provided with spaces therein at two points adjacent said opposite ends of said blade, springs received in said spaces for backing up the blade and resiliently urging, with substantially equal pressure, said ends of said blade outwardly with respect to said tool carrier, and means at the outer ends of said spaces to retain said springs entirely within said spaces.

3. Tool mounting means for an adjustable carrier member used in adjustable tools comprising a slot in the carrier member, an elongated blade slidably received in said slot and having cutting means adjacent one end thereof and work contacting guide means adjacent the other end thereof, a pair of springs in back of said blade, and constituting supporting means therefor in opposition to the work, and a leaf spring stabilizer blade secured to said tool carrier member and having an angularly directed flange located ahead of and extending toward said cutting means and contactable under pressure with the cylinder wall on which the blade operates, said elongated blade and cutting means being movable in said slot independent of said stabilizer blade.

4. Tool mounting means for an adjustable carrier member used in adjustable tools comprising a slot in the carrier member, an elongated blade slidably received in said slot and having cutting means adjacent one end thereof and work contacting guide means adjacent the other end thereof, resilient means in said slot backing said blade and biasing it outwardly in opposition to the work, and a leaf spring stabilizer blade secured to said tool carrier member ahead of said cutting means and having a rearwardly and angularly directed flange extending toward said elongated blade, said flange being under pressure produced by the resiliency of said leaf spring stabilizer.

5. A tool mounting comprising a tool carrier having a slot therein and an elongated blade in said slot having a cutting edge portion and a work contacting portion longitudinally spaced from each other, said tool carrier having a slot to receive said tool blade and said slot being enlarged at two points, springs received in said enlargements for backing up the blade and resiliently urging it outwardly with respect to said tool carrier, and a stabilizer blade formed of spring metal in sheet form with one flange located ahead of said cutting edge and secured to the tool carrier, another flange extending at an angle across the outer end of the tool carrier toward the cutting edge of said blade and contactable under resilient pressure with the cylinder wall in advance of contact by said cutting edge therewith and closely thereadjacent.
